BRUCE A. BRISTOW, OF TORONTO, ONTARIO, CANADA, ASSIGNOR OF ONE-THIRD TO
W. ALLEN CHAMBERLAIN AND ONE-THIRD TO DUDLEY A. BRISTOW, BOTH OF TO-
RONTO, CANADA.

GAME APPARATUS.

Application filed November 28, 1925. Serial No. 72,021.

This invention relates to game apparatus of the type in which one or more indicating devices are arranged to be actuated by a ball, marble or the like rolled along the surface on which the apparatus stands.

My object in the present invention is to devise a novel arrangement of supporting and tripping the indicating devices. A further object is to provide special means for reducing the effect of the impact of the ball against the apparatus, and also to provide means for assisting in preventing the escape of balls.

I attain my objects by means of the constructions hereinafter described and illustrated in the accompanying drawings in which

Fig. 1 is a perspective view of my improved game apparatus;
20 Fig. 2 a similar view of part of my apparatus showing a modification;

Fig. 3 a plan view showing a further modification of my apparatus; and

25 Fig. 4 a detail in side elevation of part of the apparatus.

In the drawings like numerals of reference indicate corresponding parts in the different figures.

1 is a base adapted to rest on a table, 30 floor, pavement or other surface. This base is shown as a wall of U-form in plan.

3 is a frame comprising a pair of uprights connected at their upper ends by a cross bar. The lower ends of the uprights are received 35 in eyes formed at the ends of the legs of the base. The parts 1 and 3 form the indicator support.

In the form shown in Fig. 1, a plurality of indicator devices 4 are pivoted on the cross bar of the frame 3. Also pivotally connected with the cross bar are a plurality of supporting and tripping levers 5, one for each indicator device. The upper end of each lever is forked and the indicating device is positioned in the recess so formed. Each indicating device will normally occupy a "set" position with its rear part supported by the lever, but its pivot point is so positioned that a sharp knock against the lower end of the lever will unbalance it and cause it to tip forwardly and downwardly as indicated in dotted lines in Fig. 4 to its "tripped" position. There being no connection between the lever and the indicating device, the lever

may return to its normal position without 55 the indicating device.

Preferably the levers will be of such a length that their free ends rest on the floor with the lever lying at an angle of approximately thirty-five degrees to the surface of 60 the floor. The particular angle, however, is not important, nor is it absolutely necessary that the end of the lever actually touch the floor, as in the latter case it would require only a slight variation in the construction 65 of the lever to support the indicating device in "set" position.

The apparatus is used by placing the indicating devices in "set" position as indicated in full lines, then rolling marbles or balls 70 along the surface of the floor in an endeavor to hit the levers and cause the latter to throw the indicating devices to "tripped" position as indicated in dotted lines.

The cross bar of the frame 3 may be made 75 of any form, such, for example, as shown in Fig. 3, so that the indicating devices will be arranged in staggered relationship to one another.

A further modification is shown in Fig. 2, 80 in which the levers and indicating devices are pivoted on a secondary bar 6 swingably supported from the cross bar of the frame. It is evident that this secondary bar 6 may be made of any form, such, for example, as 85 the shape of the cross bar in Fig. 3. An advantage derived from the mounting of the indicating devices and levers on the swingably supported secondary bar in that movement of the device due to the impact of the 90 balls striking the wall of the support is not imparted to the same extent to the secondary bar as to the main frame and there is less tendency of the impact of the balls on the 95 wall tripping the indicators.

A similar result may be attained by placing a guard 7 within but spaced from the wall, and this guard may be connected with the wall by one or more springs 8 or other resilient means tending to yieldingly hold 100 the guard in proper position.

In a preferred form both of these shock absorbing devices may be employed as the guard device tends to prevent the displacement of the apparatus as a whole as well as preventing the accidental tripping of the indicators.

The base, as before stated, will usually

be formed as a wall U-shaped in form, and the guard or bumper 7 will be similarly shaped. There will be a tendency for the balls or marbles to follow the side of the 5 guard and escape through the opening of the U. I therefore form the guard with incurved ends 2 which tend to prevent the escape of balls. The ends of the guard will preferably extend out beyond the ends of the base 10 1 so as to shield the said ends from being struck with the balls or marbles and thus removing the danger of tipping the indicators.

It will be evident that many changes in the details of construction may be made in 15 my apparatus without departing from the spirit of my invention.

What I claim is:

1. In game apparatus, the combination of a supporting bar; an indicator pivoted on 20 said bar whereby it may occupy a "set" position or a "tripped" position; and a depending lever also pivoted on said bar, said indicator, when the lever independent of the indicator is rocked, being adapted to be 25 engaged by the lever and thus moved from "set" to "tripped" position.

2. In game apparatus, the combination of a support; an indicator pivoted on said support whereby it may occupy a "set" position or a "tripped" position; and a depending 30 lever pivotally connected with said support, said indicator when in "set" position resting on the lever, but adapted to be moved to the tripped position by said lever when the latter is rocked.

3. In game apparatus, the combination of a support including a swingably mounted member; an indicator pivoted on said member whereby it may occupy a "set" position or a "tripped" position; and a depending 40 lever pivotally connected with said member, said indicator, when in "set" position, resting on the lever, but adapted to be moved to the tripped position by said lever when the latter is rocked.

4. In game apparatus, the combination of a support; an indicator pivoted on said support whereby it may occupy a "set" position or a "tripped" position; and a depending lever pivotally connected with said support, the pivoted end of said lever being forked to receive the indicator, said indicator when in "set" position being supported by the lever, but adapted, when the lever is rocked, 50 to move to "tripped" position.

5. In game apparatus, the combination of a support; a plurality of indicators independently pivoted on said support whereby each may occupy a "set" position or a "tripped" position; and a plurality of depending levers pivotally connected with said support, each of said indicators when in "set" position resting on a lever, but adapted 60 to be moved by its lever to tripped position when said lever is rocked.

6. In game apparatus, the combination of a support; an indicator pivoted intermediate its ends on said support whereby it may occupy a "set" position with its weight mainly at one side of the axis on which it moves, or a tripped position with its weight mainly on the other side of the axis on which it moves; and a depending lever pivotally connected with said support, said lever when rocked while the indicator is in set position being adapted to move the latter a sufficient distance to overbalance it so that it will move to the tripped position.

7. In game apparatus, the combination of a support; an indicator pivoted on said support whereby it may occupy a "set" position or a "tripped" position; a depending lever pivotally connected with said support, said lever being adapted to be rocked by a game piece rolled along the surface on which the apparatus stands, said indicator when the lever is rocked being adapted to move from "set" to "tripped" position; a U-shaped wall forming the base of said support; and a U-shaped bumper within and spaced from and movable relative to said U-shaped wall, the ends of the legs of said U-shaped bumper being formed with inwardly directed hooks adapted to prevent the escape of a game piece travelling in contact with the bumper.

8. In game apparatus, the combination of a support; an indicator pivoted on said support whereby it may occupy a "set" position or a "tripped" position; a depending lever pivotally connected with said support, said indicator when the lever is rocked being adapted to move from "set" to "tripped" position, said lever being adapted to be rocked by a game piece rolled along the surface on which the apparatus stands; a wall connected with said support; and a bumper spaced from movable relative to the wall and adapted to take the shock of the game piece from said wall.

9. In game apparatus, the combination of a support; an indicator pivoted on said support whereby it may occupy a "set" position or a "tripped" position; a depending lever pivotally connected with said support, said indicator when the lever is rocked being adapted to move from "set" to "tripped" position, said lever being adapted to be rocked by a game piece rolled along the surface on which the apparatus stands; a wall connected with said support; a bumper spaced from and adapted to take the shock of the game piece from said wall; and resilient positioning means between said wall and bumper.

10. In game apparatus, the combination of a support including a swingably mounted member; an indicator pivoted on said member whereby it may occupy a "set" position or a "tripped" position; a depending lever pivotally connected with said member,

5 said indicator, when in "set" position, being supported by the lever, but adapted, when the lever is rocked, to move to "tripped" position; a wall connected with said support; a bumper spaced from and adapted to take the shock of the game piece from said wall; and resilient means between said wall and bumper.

10 11. In game apparatus, the combination 10 of a support including a swingably mounted member; an indicator pivoted on said member whereby it may occupy a "set" position or a "tripped" position; a depending lever pivotally connected with said member, said 15 indicator, when in "set" position, being supported by the lever, but adapted, when the lever is rocked, to move to "tripped" position; a wall connected with said support; and a bumper spaced from and adapted to 20 take the shock of the game piece from said

wall, the ends of said bumper extending beyond the ends of the wall.

12. In game apparatus, the combination 25 of a support including a swingably mounted member; an indicator pivoted on said member whereby it may occupy a "set" position or a "tripped" position; a depending lever pivotally connected with said member, said indicator, when in "set" position, being supported by the lever, but adapted, when the 30 lever is rocked, to move to "tripped" position; and a U-shaped bumper spaced from and adapted to take the shock of the game piece from said wall, the ends of said bumper extending beyond the ends of the wall and 35 formed with inwardly directed ends.

Signed at Toronto, Canada, this eighteenth day of November, 1925.

BRUCE A. BRISTOW.
